US00D851952S

(12) **United States Design Patent** (10) **Patent No.:** **US D851,952 S**
Peterson et al. (45) **Date of Patent:** **** Jun. 25, 2019**

(54) **SEATING ARRANGEMENT**

(71) Applicant: **Steelcase Inc.**, Grand Rapids, MI (US)

(72) Inventors: **Gordon J. Peterson**, Rockford, MI (US); **Robert J. Battey**, Middleville, MI (US); **Gary Lee Karsten**, Wyoming, MI (US); **Peter A. Boeckel**, Hong Kong (HK)

(73) Assignee: **Steelcase Inc.**, Grand Rapids, MI (US)

(**) Term: **15 Years**

(21) Appl. No.: **29/605,426**

(22) Filed: **May 25, 2017**

(51) **LOC (11) Cl.** **06-01**

(52) **U.S. Cl.** USPC **D6/366**

(58) **Field of Classification Search**

USPC D6/334-336, 364, 365, 366, 374, 379, D6/380, 716, 716.1, 716.2, 716.4

(57) **CLAIM**

The ornamental design for seating arrangement, as shown.

DESCRIPTION

FIG. 1 is a perspective view of a seating arrangement embodying the present invention;

FIG. 2 is a front elevational view of the seating arrangement;

FIG. 3 is a first side elevational view of the seating arrangement;

FIG. 4 is a rear elevational view of the seating arrangement;

FIG. 5 is a second side elevational view of the seating arrangement;

FIG. 6 is a top plan view of the seating arrangement; and,

FIG. 7 is a bottom plan view of the seating arrangement.

The broken lines shown in the drawing are for the purpose of illustrating environmental structure and form no part of the claimed design.

1 Claim, 7 Drawing Sheets
